UNITED STATES PATENT OFFICE.

WILEY JONES, OF NORFOLK, VIRGINIA.

BOOT OR SHOE STRETCHER.

SPECIFICATION forming part of Letters Patent No. 352,134, dated November 9, 1886.

Application filed March 18, 1885. Renewed May 18, 1886. Serial No. 202,589. (No model.)

To all whom it may concern:

Be it known that I, WILEY JONES, a citizen of the United States, residing at Norfolk, in the county of Norfolk and State of Virginia, have 5 invented certain new and useful Improvements in Boot or Shoe Stretchers, of which the following is a specification.

My invention has general reference to boot and shoe stretchers, and its object is the production of an implement capable of stretching a boot or shoe across the balls, at the instep, and in length, all by means of one last and one main operating-screw in a manner hereinafter first fully set forth and described, and then pointed out in the claims.

In the drawings, which serve to illustrate my invention more fully, and form a part of this specification, Figure 1 is a side view of the last as used in stretching the shoe across the balls. Fig. 2 is a view of the bottom of the last. Fig. 3 is a vertical central section. Fig. 4 is a horizontal section on the line xx of Fig. 3. Fig. 5 shows the stretcher as used for the instep. Fig. 6 shows the act of stretching the shoe lengthwise. Fig. 7 shows the swivel-nut P. Fig. 8 is the heel-brace. Fig. 9 is the bottom plate; Fig. 10, the clamping-cap.

Like parts are designated by corresponding letters of reference in all the figures.

The last consists of two side pieces, A A, made preferably of iron, and a bottom plate, D. The side pieces are connected by a hinge, N, at the heel, and the bottom plate is connected to one of the pieces, near the toe, by a pin running 35 through the arms O O, and fastened into the side piece, one end of the pin extending far enough beyond one of the arms to work detachably in the opposite side piece. In each of the side pieces is a groove, E, deepest at the widest part 40 of the last and shallowing out toward the toe, as seen in Fig. 4. In this groove is a sub-groove, F, along which runs one of the wheels J J. At the heel of the last, in each side, are the orifices B B, in which the arms of the screw-threaded 45 nut P bear detachably.

To stretch the shoe across the balls, I turn the screw C with the arms of the nut P bearing in the lower orifice B of each side of the last. This forces the wheels J and J along the sub-grooves F and F, which motion expands the two side pieces, as shown in Figs. 3 and 4.

To stretch the instep, I detach the screw C

from the large nut H by unscrewing the toe-pusher I. Then I rest the screw-threaded swivel-nut G, which is attached to the end of C, in 55 the cavity L of the bottom plate, and the arms of nut P in the upper orifice B of each side piece, and turn the screw C, thereby forcing the side pieces, A A, with their clamping-cap K, upward, as shown in Fig. 5. This cap is only 60 used while the instep is being stretched, and gives the desired curve to the top of the last, and also holds the side pieces together by means of two headed pegs that project from its under surface and gear each into a slotted aperture, 65 S, in each side piece of the last. The apertures T in this cap are similar to those in the side of the last, and are intended for the usual bunion-caps.

To stretch the shoe in length, I detach the 70 screw C from the last and screw the toe-pusher I into the screw-threaded swivel-nut G, and screw the heel-brace R upon the arm Q of the nut P. Then, on turning the screw C, the heel-brace is pressed against the counter, and the 75 toe-pusher by a reciprocal motion is forced against the upper leather of the toe, as clearly shown in Fig. 6. This toe-pusher, while partly resembling the common and old bunion-caps, differs from them in that the pin is much longer 80 and contains a screw-thread which holds the pusher in position better than a smooth pin can; also, in that it is a compound instrument, being used not only as a toe-pusher, but also to hold together the nuts H and G while the shoe 85 is being stretched wider.

Having thus described my invention, what I claim as new, and desire to secure by Letters Patent, is—

1. The combination, in a boot or shoe 90 stretcher having the screw C and hinge N, of a pronged nut, P, moved along the said screw, and a swivel-nut, G, secured to the end of said screw, as and for the purposes described and set forth.

2. The combination, in a boot or shoe 95 stretcher having the screw C and hinge N, of wheels J J and a nut, H, carrying the said wheels, as and for the purposes set forth and described.

3. In a boot or shoe stretcher, the parts A A, provided with the grooves E and sub-grooves F, forming a track for wheels J J, substantially as set forth.

4. The combination, in a boot or shoe stretcher having the screw C and hinge N, of side pieces, A A, provided with the lower orifices B, through which orifices oscillate the smooth prongs of nut P, all arranged substantially as shown and described.
5. The combination, in a boot or shoe stretcher having the screw C and hinge N, with the side pieces, of a bottom plate, D, provided with a cavity, L, and attached to one of the side pieces, all as shown and described.
6. The combination, in a boot or shoe stretcher having the screw C and hinge N, of the side pieces with an arm or arms, O, for securing the bottom plate to one of the side pieces, as and for the purposes described.
7. The combination, in a boot or shoe stretcher having the screw C and hinge N, with the parts A A, provided with upper orifices B,
- of nut P, and aperture M, in which oscillate the screw C, all arranged substantially as and for the purposes described.
8. The combination, in a boot or shoe stretcher having the screw C, of a screw-threaded toe-pusher, I, and a heel-brace, R, said brace working detachably on the nut P by means of a screw-arm, Q, projected from the body of said nut, as and for the purposes described.
9. The combination, in a boot or shoe stretcher having the hinge N and screw C, of the parts A A, provided with the elongated slots S S, with the cap K, provided with the pins U U, substantially as shown and described.

WILEY JONES.
